US0D1075695S

(12) **United States Design Patent** (10) **Patent No.:** **US D1,075,695 S**
(45) **Date of Patent:** **** May 20, 2025**

(54) **CONTACT PIN FOR INTEGRATED CIRCUIT
TESTING**

(71) Applicant: **Johnstech International Corporation**, Minneapolis, MN (US)

(72) Inventor: **Melissa Hasskamp**, Minneapolis, MN (US)

(73) Assignee: **Johnstech International Corporation**, Minneapolis, MN (US)

(**) Term: **15 Years**

(21) Appl. No.: **29/917,131**

(22) Filed: **Nov. 17, 2023**

Related U.S. Application Data

(63) Continuation-in-part of application No. 29/843,097, filed on Jun. 17, 2022, now Pat. No. Des. 1,042,346, which is a continuation-in-part of application No. 29/833,520, filed on Apr. 5, 2022, now Pat. No. Des. 1,042,345.

CLAIM

The ornamental design for a contact pin for integrated circuit testing as shown and described.

DESCRIPTION

FIG. 1 is a Top Front Right Side Perspective view of a contact pin for integrated circuit testing showing my new design.

FIG. 2 is a Bottom Rear Left Side Perspective view thereof. FIG. 3 is a Front view thereof.

FIG. 4 is a Rear view thereof.

FIG. 5 is a Left view thereof.

FIG. 6 is a Right view thereof.

FIG. 7 is a Top view thereof; and,

FIG. 8 is a Bottom view thereof.

1 Claim, 6 Drawing Sheets
